UNITED STATES PATENT OFFICE.

ALVIN TAPLIN, OF FORESTVILLE, CONNECTICUT, ASSIGNOR TO THE BRISTOL BRASS AND CLOCK COMPANY, OF SAME PLACE.

WICK-RAISER FOR LAMPS.

SPECIFICATION forming part of Letters Patent No. 404,121, dated May 28, 1889.

Application filed October 10, 1888. Serial No. 287,765. (No model.)

To all whom it may concern:

Be it known that I, ALVIN TAPLIN, of Forestville, in the county of Hartford and State of Connecticut, have invented a new and useful Improvement in Wick-Raisers for Lamps, of which the following is a specification.

I will describe in detail a lamp embodying my improvement and then point out the novel features in claims.

10 In the accompanying drawings, Figure 1 is a vertical section of a lamp embodying my improvement. Fig. 2 is a plan or top view of a certain cap and portion of a wick-tube employed therein.

15 Similar letters of reference designate corresponding parts in both the figures.

A designates the reservoir or fount of the lamp.

B designates the base of the lamp.

20 C designates a cylindrical tube constituting the inner wall of the wick-tube. Air may ascend freely through the inner wall of the wick-tube to the inner side of a flame emanating from the burner-tip.

25 D designates a post, in the upper end of which is detachably secured a button or spreader, D', by which the ascending column of air is deflected against the flame.

D² designates a conical air-distributer arranged in the central draft-flue and surrounding the post D.

E designates a cap for the reservoir. (Shown more clearly in Fig. 2.) The upper portion of the reservoir is provided with a cylindrical aperture, and about the edges of this aperture a flange, a, extends upwardly. The cap E in this example of my improvement is provided with a downwardly-extending flange, a', of such diameter that it will fit snugly within

40 the flange a. I have shown upon the cap an annular bead, a², which rests upon the upper edge of the flange a when the cap is in place. In the example of my improvement shown the cap has formed integral with it an upwardly-extending cylindrical portion, b, which portion constitutes the outer wall of the wick-tube.

F designates a perforated air-distributer surrounding the upper portion of the wick-tube, by which air is supplied to the exterior 45 of the flame. This distributer comprises also

a chimney-gallery provided with the usual spring-fingers, c. The cap E may be secured to the reservoir by a bayonet-lock, d, or in any other suitable manner. It may be readily removed from the lamp, when it is desired to fill 55 the reservoir or to gain access to the interior thereof, by unlocking it and lifting it upwardly, and it may be as readily restored to its proper position.

G designates a wick-carrier, here shown as 60 a ring, surrounding the wick near the lower end of the latter and secured thereto by means of prongs or teeth g.

H H' designate a wick-raiser. The portion H of the wick-raiser, as here shown, consists 65 of a flat piece of metal, which strip of metal has near its lower extremity an offset or bent portion, f, which offset or bent portion is secured to the wick-carrier d. It may be thus secured by solder or otherwise. This portion 70 H of the wick-carrier extends upwardly through the cap E. I have shown the cap E as provided with a suitable aperture, in which is secured a sleeve, e, through which the portion H of the wick-raiser extends, and which 75 acts as a guide therefor. The portion H' of the wick-raiser consists in this example of my improvement of a rod passing downwardly through a tube, I, which tube extends through the reservoir A and opens both above and below the latter. The tube I may be secured in the reservoir by solder or otherwise. I have shown the upper part of the portion H' of the wick-raiser as having a bent or offset arm, h, extending at approximately right angles to the 80 direction of the length of the main body of the portion H'. The arm h is adapted to be passed loosely through a suitable aperture in the portion H of the wick-raiser. It may be thus engaged by bending or deflecting the upper part of the portion H, which is resilient, and then inserting the arm h in said aperture. By bending or deflecting the upper part of the portion H the arm h may be as readily disengaged from the portion H, and may be swung 85 round and away from the portion H, as shown in dotted outline. When the arm h has been disengaged from the portion H, the cap may be readily removed from the reservoir and as readily replaced thereon. The portion H' of 90

95 100

the wick-raiser extends below the reservoir, and its lower portion is shown as screw-threaded. With this screw-threaded portion engages a nut, J, upon which is secured a 5 hand-piece, J'. The nut may rotate within a shell, j, secured to the body of the reservoir. By rotating the nut the portion H' may be raised or lowered, and when in engagement with the portion H will of course cause the 10 raising and lowering of the wick.

What I claim as my invention, and desire to secure by Letters Patent, is—

1. In an Argand lamp, the combination, with a reservoir, of a wick-tube, a wick-carrier, and 15 a wick-raiser connected to the wick-carrier and having a portion extending upwardly above the reservoir, said portion being resili-ent, and a portion extending downwardly be-
low the same provided with an arm above the

reservoir adapted to be swung around to en- 20 gage said first-named portion and around out of engagement therewith, substantially as specified.

2. In an Argand lamp, the combination, with a reservoir, of a wick-tube, a wick, a wick-car- 25 rier, and a wick-raiser connected to the wick-carrier and having a portion extending up-wardly above the reservoir and provided with one or more apertures, and another portion extending downwardly below the reservoir, 30 the last-named portion being provided above the reservoir with an arm engaging one of said apertures, substantially as specified.

ALVIN TAPLIN.
